UNITED STATES PATENT OFFICE.

HENRY SWINDELL, SAMUEL R. SMYTHE, AND JAMES B. SWINDELL, OF ALLEGHENY, PENNSYLVANIA.

REGENERATIVE FURNACE.

SPECIFICATION forming part of Letters Patent No. 414,874, dated November 12, 1889.

Application filed April 3, 1889. Serial No. 305,874. (No model.)

To all whom it may concern:

Be it known that we, HENRY SWINDELL, SAMUEL R. SMYTHE, and JAMES B. SWINDELL, citizens of the United States, residing at Allegheny, in the county of Allegheny and State of Pennsylvania, have invented or discovered certain new and useful Improvements in Annealing-Furnaces, of which improvements the following is a specification.

10 Great difficulty has heretofore been experienced in annealing large sheets or plates of metal—such as saws—on account of the difficulty of uniformly heating both sides of the sheets or plates, one side being protected by 15 the bed of the furnace on which they rest during the annealing operation.

The invention described herein relates to certain improvements in furnaces for reheating or annealing plates or sheets of metal or 20 other material, and has for its object a construction of furnace wherein heat can be applied with practical uniformity on both sides of the plates or sheets, thereby preventing any warping or other distortion incident to 25 unequal heating.

The invention is more fully hereinafter described and claimed.

In the accompanying drawings, forming a part of this specification, Figure 1 is a sectional elevation of the furnace, the plane of section being at right angles to the regenerative chambers. Fig. 2 is a similar view, the plane of section being at right angles to that on which Fig. 1 is made. Fig. 3 is a sectional 30 plan view of the body portion of the furnace, the plane of section being indicated by the line $\alpha\alpha$, Fig. 1; and Fig. 4 is a horizontal section taken on the line yy , Fig. 1.

In the practice of our invention the regenerative chambers 1 and 1^a , 2 and 2^a for the gas and air are constructed in all essential particulars similarly to the ordinary form of regenerative furnaces, and are provided with the usual flues or conduits for conducting the 40 gas and air to and conducting the products of combustion away from the furnace, and with suitable regulating-valves. On top of these regenerative chambers are formed the bottoms of the combustion-chambers 3 3^a , &c., the tops 45 of said combustion-chambers being formed by the floor 4 of the heating-chamber, consisting

of a series of tiles or bricks, preferably interlocked, as shown in Fig. 1, and supported by a series of transverse partitions 5, extending entirely across the body of the furnace. 55 Each of these chambers is connected at or near one end thereof with the gas and air regenerative chambers on one side of the furnace by flues 6 and 7, and is connected with the heating-chamber or portion of the furnace 60 above the floor by a passage 8 at the end opposite that at which the inlet-flues are arranged.

By reference to Fig. 3 it will be seen that each alternate combustion-chamber is connected to the regenerative chambers on one side of the furnace, the other chambers being connected to the regenerative chambers on the opposite side of the furnace—that is to say, the combustion-chamber 3 is connected 65 to the regenerative chambers 1 and 2 by flues 6 and 7, while the next adjacent chamber 3^a is connected to the regenerative chambers 1^a and 2^a by flues 6^a and 7^a ; and it will also be observed that the combustion-chamber 3 is 70 connected by its passage 8 to the portion of the furnace above the floor 4 on that side of the furnace on which the flues 6^a and 7^a connect the combustion-chamber 3^a with the regenerative chambers 1^a and 2^a , as shown in 75 Fig. 3. Each combustion-chamber is provided at that end at which the flues 6 and 7 enter with a port or passage 9, leading through the outer wall of the furnace, through which access may be had for the purpose of igniting 80 the gas.

In describing the operation of our furnace we will suppose that the valves or dampers are so adjusted that the gas and air will enter in through the regenerative chambers 1^a 90 and 2^a , and the products of combustion will pass out to the stack through the regenerative chambers 1 and 2. The gas and air pass from the regenerative chambers 1^a and 2^a up through the flues 6^a and 7^a on one side of the 95 furnace into alternate combustion-chambers 3^a , 3^b , 3^c , and 3^d , thence along said combustion-chambers to the passages 8^a at the opposite ends thereof into the portion of the furnace above the floor 4, thence across such 100 floor to the opposite side of the furnace, where they pass down the passages 8 into the com-

bustion-chambers 3, 3^b, 3^d, and 3^f, thence along said combustion-chambers to the flues 6 and 7, down such flues into the regenerative chambers 1 and 2, and thence to the 5 stack. By a reversal of the valves and dampers the flame and products of combustion will pass along the flues 3, 3^b, 3^d, and 3^f, up through the passage 8, into the portion of the furnace above the floor 4, down the passages 8^a on the 10 opposite side of the furnace, along the combustion-chambers 3^a, 3^c, 3^e, and 3^g to the flues 6^a and 7^a, thence through the regenerative chambers 1^a and 2^a to the stack. Thus it 15 will be seen that the flame and products of combustion in each case pass twice along the floor 4 of the heating-chamber and once over the top of the same, thereby thoroughly heating the floor and the under side of any article resting thereon, as well as the upper side 20 of such article, and by such uniform application of the heat to both sides of the article prevent any tendency to warping or distortion of the same.

We claim herein as our invention—

25 1. In an annealing or heating furnace, the combination of a series of combustion-chambers extending across the furnace below the floor of the heating-chamber, passages connecting each of said chambers at one end 30 thereof with the heating-chamber, two sets of

gas and air regenerative chambers, a series of flues connecting one set of regenerative chambers with part of the combustion-chambers at the ends opposite those connected with the heating-chamber, another series of flues similarly connecting the other set of regenerative chambers with the other combustion-chambers, and means for reversing the flow of gas and air and products of combustion, substantially as set forth. 35

2. In an annealing or heating furnace, the combination of a series of combustion-chambers extending across the furnace below the floor of the heating-chamber, passages connecting said chambers at alternately-opposite 40 ends to the heating-chambers, gas and air regenerative chambers, flues connecting said regenerative chambers with the combustion-chambers at the ends opposite those connected to the heating-chambers, and igniting 45 flues or ports communicating with the combustion-chambers, substantially as set forth. 50

In testimony whereof we have hereunto set our hands.

HENRY SWINDELL.
SAMUEL R. SMYTHE.
JAMES B. SWINDELL.
